UNITED STATES PATENT OFFICE.

FRANCES LYNX, OF NEW YORK, N. Y.

SAFETY-HOOK.

SPECIFICATION forming part of Letters Patent No. 732,308, dated June 30, 1903.

Application filed November 3, 1902. Serial No. 129,941. (No model.)

To all whom it may concern:

Be it known that I, FRANCES LYNX, a citizen of the United States, residing at New York city, in the county of New York and State of New York, have invented certain new and useful Improvements in Safety-Hooks, of which the following is a specification.

My invention relates to improvements in hooks used for carrying different articles—such as eyeglasses, watches, skirt-lifters, &c.—my hook being constructed in such a way as to make the falling out or tearing off of the things carried in them impossible. The way in which I do this is shown in the accompanying drawings, in which—

Figure 1 is a side view of the hook with uplifted ring, one part, the needle-point, being broken off at *m*. Fig. 2 is a front view of the complete hook with uplifted ring. Fig. 3 is a side view of the hook from the right-hand side when closed.

Similar letters refer to similar parts throughout the several views.

A wire of required length is bent at *a*, as shown in Fig. 2, both parts of the wire running closely together and parallel to each other up to *c* in a light convex curve. From *b* to *c* it is bent first in a concave and then in a convex curve. At *c* the double wire forms a loop and then runs up to *d*, at which point the two ends of wire are used for different purposes. The one end *e* (shown in front in Fig. 3) is wound in a full circle and a half forming the spring part of a safety-pin, the end being cut off at the required length and pointed to a needle-point. The other end *f* is bent at *d* only around a half-circle. At the end of the required length it carries a point-protector,

as used in safety-pins. At *d* both parts are 40 connected by a little plate *i* to keep them in close connection. A ring *g* is slipped through the spring-ring of *e* and around the other wire *f*, hanging in there loosely. It has to be large enough to reach over the first part 45 of the hook *a b* when the same is pressed back to touch the part *c d*. The ring can be shaped like a key-ring cut longitudinally in a spiral line, as usual, or it can be slipped in before fully bent together and then brazed 50 or soldered. In Fig 2 this ring *g* is shown in an uplifted position, in which it will be held to enable the hooking in of either another ring *h*, carrying a watch, skirt-lifter, &c., or the bridge of a pair of eyeglasses, &c. After 55 this object is hooked in the ring *g* is drawn over the hook *a b*, and after having passed a will resume the position as shown in Fig. 3.

What I claim as my invention, and desire to secure by Letters Patent, is—

A double-bent hook made of double-folded wire, one end formed into a safety-pin point, the other end having a spring-bend and a point-protector to said safety-pin point, in combination with a ring *g* running through 65 and held in position by the spring-bend of the safety-pin, and adapted to slide over the bent part *a b* of the hook, thus securing the safe closure of the hook substantially as described.

In testimony whereof I have signed my name to this specification in presence of two subscribing witnesses.

FRANCES LYNX.
